[57] **CLAIM**

The ornamental design for a baking dish or the like, as
shown and described.

DESCRIPTION

FIG. 1 is a top plan view of a baking dish or the like
showing my new design.

FIG. 2 is a front elevational view, with the back eleva-
tional view being identical.

FIG. 3 is a bottom plan view.

FIG. 4 is an elevational view in section taken along line
4—4 of FIG. 1.

FIG. 5 is an end elevational view, with the opposite end
elevational view being identical.

FIG. 6 is an enlarged fragmental sectional view in ele-
vation of an edge portion shown in FIG. 4.
